UNITED STATES PATENT OFFICE.

ERNST DORING, OF NEW YORK, N. Y.

WARDROBE-BED.

SPECIFICATION forming part of Letters Patent No. 309,530, dated December 23, 1884.

Application filed December 1, 1883. (No model.)

To all whom it may concern:

Be it known that I, ERNST DORING, of the city, county, and State of New York, have invented a new and useful Improvement in 5 Wardrobe-Beds, of which the following is a full, clear, and exact description.

Reference is to be had to the accompanying drawings, forming a part of this specification, in which similar letters of reference indicate 10 corresponding parts in all the figures.

Figure 1 is a sectional side elevation of my improvement, shown as folded, part being broken away. Fig. 2 is a sectional side elevation of the same, shown as opened for use, 15 part being broken away. Fig. 3 is a sectional plan view of the same, taken through the line *x x*, Fig. 2. Fig. 4 is a side elevation of the supporting and hinging gear-brackets enlarged.

20 The object of this invention is to facilitate the opening and closing of folding beds, and also to promote strength, durability, and security in the construction of such beds.

The invention consists in a folding bed constructed with the upright case, and the bed-frame connected by a bar having end shoulders, a smooth section, and a toothed section separated by a recess, and an angular bar having a smooth section and a curved toothed 25 section, whereby the fulcrum-point will be changed automatically as the bed-frame is lowered and raised, and the bed-frame will be prevented from going too far in either direction. The weight-carrying board is connected 30 with the bed-frame by eye-plates, pivots, and pivot-bars, so that the said weight-carrying board will be free to move up and down as the bed is opened and closed. The weight-carrying board is provided with guide-bars, to 35 rest and slide upon guard-boards connected with the stationary case by angle-irons, to keep the weight-board and its attached weights in place as they move up and down. To the weight-board are attached recessed 40 brackets, to form a pocket to receive the weights, as will be hereinafter fully described.

A represents the stationary part or case of the bed, and B is the folding part or bed-frame, which is so formed as to fold up into 45 the case A. The lower parts of the sides of the case A are extended forward, and to them

are attached the lower parts, C, of the supporting and hinging brackets, which parts C are made in the form of a bar having upwardly-projecting shoulders 1 2 at its rear and forward ends, to serve as stops to the upper parts, D, of the said brackets. The upper edge, 3, of the bar C from the shoulder 1 forward for about one-third of its length is made smooth, and the forward part of the said edge 60 is provided with teeth 4.

In the upper edge of the bar C, at the point of meeting of the smooth part 3 and the toothed part 4, is formed a recess, 5, to receive the angle of the upper part, D, hereinafter described.

The upper part, D, of the brackets is made in the form of an angular bar, and is attached to the side boards of the bed-frame B in such a position that the smooth edge 6 of the lower arm of the said bar will be at right angles with the smooth edge 3 of the bar C when the bed is opened, as shown in Fig. 2, and parallel with and resting upon the said edge 6 when the bed is closed, as shown in Fig. 1. 70 The edge 7 of the forward arm of the bar D is curved and toothed, to engage with the toothed edge 4 of the bar C, as shown in Fig. 2. With this construction, when the bed is fully opened, the point of contact between the bars C D will be at the forward ends of the said bars, and as the bed is being closed the said point of contact will move gradually to the rearward. In opening the bed the fulcrum-point or point of contact between the 75 bars C D is moved gradually forward or toward the center of the bed-frame, so that the operator will have the greatest advantage of leverage when the greatest weight is to be sustained. As the bed is opened and closed 80 the angle 8 at the forward end of the smooth edge 6 enters the recess 5 of the bar C, and serves as a pivot until the teeth 7 of the bar D come into contact with the teeth 4 of the bar C.

To the rear upper corners of the side boards of the bed-frame B are attached upwardly-projecting eye-plates E, in the eyes of which are pivoted pins F, formed upon or attached to the lower ends of the bars G. The upper 90 ends of the bars G are attached to the lower corners of the board H, to the outer side of the

ends of which are attached the lower ends of bars I. The upper ends of the bars I project to rest against and slide upon the guard-boards J, secured to the side boards of the case A by angle-irons K, or other suitable means that will form a connection of the necessary strength to support the said boards against the outward pressure of the guide-bars I.

To the end parts of the outer side of the board H are attached the flanged inner edges of the brackets L, the adjacent sides of which are recessed, as shown in Figs. 1, 2, and 3, so that the two brackets L form an open pocket to receive the weights M, to balance the bed-frame B and allow it to be easily opened and closed.

Having thus described my invention I claim as new and desire to secure by Letters Patent—

1. In a folding bed, the combination, with the stationary upright case A and the bed-

frame B, of the bar C, having end shoulders, 1 2, smooth sections 3, toothed section 4 and recess 5, and the angular bar D, having smooth section 6 and curved toothed section 7, substantially as herein shown and described, whereby the fulcrum-point will be changed automatically, and the bed-frame will be prevented from going too far in either direction, as set forth.

2. In a folding bed, the combination, with the board H, having recessed bracket L for carrying the weight, guide-bars I, guard-boards J, angle-irons K, and the stationary upright case A, of the movable bed-frame B, 35 eye-plates E, pivots F, and pivot-bars G, substantially as shown and described.
